UNITED STATES PATENT OFFICE.

CHRISTIAN GIELOW, OF DUSSELDORF-OBERKASSEL, GERMANY.

ROLLING MILL.

Application filed November 22, 1927, Serial No. 235,053, and in Germany November 25, 1926.

- This invention relates to a rolling-mill for purifying and opening clay, loam and similar materials. I am aware of the existence of rolling-mills so designed as to be adapted to 5 remove automatically foreign bodies, such as lime, stones, brown-coal and the like. All known machines suffer however from quick obstruction, strong wear and tear, and great consumption of power.
- 10 These drawbacks are obviated by my present invention which relates to a rolling-mill, in which the clay or the like is not only purified, but also opened. This improved rolling-mill is illustrated diagrammatically and by 15 way of example on the accompanying drawing on which
- Fig. 1 is a vertical longitudinal section through the mill, and
- Fig. 2 a horizontal section through the 20 same.
- On the drawing *a* denotes a cylinder with a smooth circumferential surface, and *b* is a cylinder or drum provided with longitudinal ribs *b'*. The cylinder *a* is affixed to a shaft *c* supported in bearings *f* and *g*, and the cylinder *b*, *b'* is affixed to a shaft *d* supported in bearings *e* and *h*. The bearings themselves are supported on girders *i* and *k*. The shaft *c* is provided with a pulley *l* and the shaft *d* is provided with a pulley *m*. Power is applied to the two cylinders by these pulleys which are driven from any suitable source of power. The material to be treated between the smooth cylinder *a* and the ribbed cylinder *b*, *b'* is supplied to these cylinders through a hopper *p*, *q* or the like. *n* denotes a scraper removing from the cylinder *a* the material adhering to it.
- The cylinders are rotated with very different speeds wherein resides an important 40 and characteristic feature of the invention. The number of revolutions of the cylinder *a* amounts to about one hundred per minute, whereas the cylinder *b* performs only very few revolutions in a minute, say 2. I wish it, 45 however, to be understood, that these numbers are stated merely by way of example. They may be varied according to the material to be treated and to the condition of the same.
- When the material to be treated is introduced into the hopper *p*, *q* and supplied by it to the cylinders, it is squeezed by the quickly rotating cylinder *a* into the spaces between the ribs of the slowly rotating cylinder *b*, *b'*, until these spaces are completely filled up. 55 Assuming the material be clay, then the cylinder *b*, *b'* will be converted so to say into an elastic clay cylinder, the circumferential surface of which contacts with the smooth circumferential surface of the cylinder *a*. The 60 contacting surfaces exert a pulling action upon the material present between them and the feed-hopped, and a certain amount of the material is constantly withdrawn from the supply and converted into a sheet *x*, as shown 65 in Fig. 1. The impurities contained in the material supplied from above, i. e. stones, and the like, are, however, retained in the spaces between the ribs *b'*, that is to say, they are retained within the material present between 70 the ribs, and they can be retained therein owing to the material being a soft mass in which the hard impurities are not crushed, as is the case with the known rolling-mills mentioned in the introductory part of this specification. 75
- In the same measure in which the hard impurities enter into the soft material present between the ribs, a corresponding amount of the soft material is pressed out of said spaces 80 and is caused to leave the machine by joining the sheet *x*.
- They are, of course, provided means (not shown) for adjusting the cylinders relatively to one another, that is to say, the gap which must exist between the cylinders in order to let pass the sheet *x* can be varied according to the requirements. When finally, the spaces between the ribs *b'* are practically completely 90 filled with the impurities, the mill is stopped and the said spaces are emptied, or cleaned respectively.
- The cylinder *b*, *b'* may be completely open around its circumference, but it is as well possible to provide it with a casing or jacket extending from the feed-hopper to the place where the sheet *x* leaves the mill. A casing or jacket of this size is indicated in Fig. 1 by the dotted line denoted *r*. 95
- What I claim is:
1. A rolling mill for purifying and opening clay, loam or the like, comprising, in combination, a rotary cylinder having a solid circumferential surface, another rotatory cylinder, means on the surface of said cylinder to receive and hold on its circumferential surface a layer of the material to be purified and opened, and means for rotating the first-mentioned roller with a speed considerably higher than the speed of the other cylinder and in opposite directions to each other, substantially as set forth. 100
- 105
- 110

2. A rolling mill for purifying and opening clay, loam or the like, comprising, in combination, a rotatory cylinder having a solid circumferential surface, another rotatory cylinder having longitudinal ribs on its circumferential surface and adapted to receive and hold in the spaces between said ribs por-

tions of the material to be purified and opened and to cause this material to form a layer around it, and means for rotating said cylinders with different speeds and in opposite directions. 10

In testimony whereof I affix my signature.
CHRISTIAN GIELOW.
